UNITED STATES PATENT OFFICE.

ALICE MORGANSTERN, OF NEW YORK, N. Y.

BLOOMERS.

Application filed April 3, 1923. Serial No. 629,541.

To all whom it may concern:

Be it known that I, ALICE MORGANSTERN, a citizen of the United States, residing at New York city, in the county of New York and State of New York, have invented certain new and useful Improvements in Bloomers, of which the following is a specification.

This invention relates to bloomers, an object of the invention being to provide an improved garment of this kind comprising a body portion terminating in an elastic waist band and leg portions terminating in elastic knee bands, the present improvement embodying features adapted to enable the garment to be put on or removed quickly and easily. Furthermore, by virtue of the present improvement the bloomers will be more durable and lasting in use, and more convenient to the user than garments of this kind heretofore made.

A further object of this invention is to provide improved bloomers comprising a body portion having an adjustable elastic fit at the waist and also comprising leg members having each an elastic fit adjacent to the knee, and wherein the bloomers may be removed and put on without having to pull them over the feet and legs, which has been difficult to accomplish due to the continuous tight fitting elastic bands at the waist and knees, this resulting after continued use in stretching out the elastic thereby necessitating the renewal or replacement thereof.

35 A further object of this invention is to provide an improved pair of bloomers having an opening at the outer side thereof extending from the top to the bottom edge thereof, the free edges being releasably connected together so as to permit the garment to be put on and removed with great ease and convenience, the bloomers also having a releasable elastic fit at the waist and also adjacent to the knee.

45 Other objects of this invention will appear in the following description and appended claims, reference being had to the accompanying drawings forming a part of this specification wherein like reference characters indicate corresponding parts in the several views and wherein Fig. 1 is a front view illustrating a present form of my invention; Fig. 2 is a side elevation and Fig. 3 is a fragmentary enlarged view illustrating the waist band.

Before explaining in detail the present

improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

In the drawings I have illustrated a present preferred form of my invention and it will be seen that the pair of bloomers comprise a front portion A, and a rear portion or member B, the two members being separable throughout the outer sides thereof and adapted to be releasably joined together along these opposite sides in order to form a complete pair of bloomers. The front member A comprises a pair of panels 9 and 11 stitched together at 9^a, and the rear member B also comprises a pair of complementary panels 10 and 12 stitched together in like manner, the panels or leg portions 9 and 10 being stitched together at 50 and the portions 11 and 12 stitched together at 51. It will be seen that the sides 9 and 10, and sides 11 and 12, may be joined together along the outer sides of the garment to form the bloomer legs and also to connect the garment about the waist. The front and rear members A and B may be spread out lengthwise and flatwise so as to facilitate ironing the garment.

It will be seen that the portions 9 and 10 are separated by means of a vertical opening 13 at the outer side thereof, and the portions 11 and 12 are likewise separated by means of an opening 14 at the opposite side of the garment. The opening 13 is closed by means of a projecting flap or tab 15 extending from the edge of the rear panel 10, this flap overlapping the opposed edge of the panel 9 and being releasably connected thereto by means of suitable fastening devices 16, which may be in the form of snap fasteners. Adjacent to the flap 15 is a similar flap or tab 17 extending from the free edge of the panel 9 but in the opposite direction, so as to overlap the panel 10. This flap 17 is releasably connected to the rear panel by suitable fastening devices 18, which also may be in the form of snap fasteners.

The opening 14 at the opposite side of the bloomers is closed in substantially the same manner, the rear panel 12 having a projecting flap 19 foldable over upon the front

panel 11 and detachably connected thereto by means of fastening devices 20. The front panel 11 also has a projecting flap 21 adapted to fold over the edge of the rear panel 12 5 and detachably connected thereto by fastening devices 22.

The front and rear panels 9 and 10 which form one of the legs of the garment are gathered together at the lower part thereof 10 and terminate in a tubular hem having an elastic inserted therein, forming an elastic band 23. The free ends of the elastic knee band 23 may be detachably connected together at the opening 13 by means of suitable fastening devices 24 and 25, in the present instance, these comprising a hook and eye fastener. The opposite leg member of 15 the garment is gathered at the lower portion thereof and likewise terminates in an elastic knee band 26, the free ends thereof being detachably connected together by means of fastening devices 27 and 28. When the garment is put on the elastic bands 23 and 26 20 may be readily hooked around the legs and 25 will resiliently embrace the legs so as to assist in supporting the garment.

The front and rear portions of the bloomers terminate at the upper edges thereof in an elastic waist band.

30 In the present instance, this waist band comprises alternate inelastic portions or strips 29 connected together by alternate elastic portions 30, the latter comprising tubular hems having elastic strips 30^a inserted therein. By virtue of this construction a waist band is provided which has sufficient elasticity or resiliency to provide the necessary snug and adjustable fit at all times, but also greater comfort is obtained 35 at the sides and front of the waist or body portion due to the fact that the upper parts of the bloomers are smooth and not gathered at these points. At opposite sides of the garment the free edges of the waist bands 40 are detachably connected together by means of suitable fastening devices 31, in the present instance these comprising hooks and eyes.

45 From the foregoing construction it will be seen that the present garment may be readily and easily put on and removed without having to draw the same over the feet and legs, and thereby stretching and wearing out the elastic bands at the waist and legs. The opposite leg members may be 50 readily fastened about the body at opposite sides merely by connecting together the fastening devices at the outer side of each leg member. Not only are the free ends of 55 the elastic waist band and the elastic leg portions 23 and 26 readily connected together, but the oppositely located flaps and closure members 15 and 17, or 19 and 21 are readily fastened in position so as to effectually close the openings 13 and 14 and fasten

the garment about the body of the wearer. The construction and interlocking relation of the oppositely located closure flaps results in effectually resisting and preventing the juxtaposed connected edges of the opening 70 13 or 14 from inadvertently or accidentally separating or pulling apart, the flaps 15 and 17 for instance, one extending from the free edge of each leg portion, forming at the side of the garment substantially an interlocking 75 connection.

It is to be understood that by describing in detail herein any particular form, structure, or arrangement, it is not intended to limit the invention beyond the terms of the 80 several claims or the requirements of the prior art.

Having thus explained the nature of my said invention and described a way of constructing and using the same, although 85 without attempting to set forth all of the forms in which it may be made, or all of the modes of its use, I claim:

1. As an article of manufacture, a pair of bloomers comprising a body portion terminating in an elastic waist band and having a pair of leg members terminating in elastic knee bands, said body portion and a leg member having a vertical opening at the outer side extending through the elastic 90 waist band and the elastic knee band, and fastening means for releasably connecting the free ends of the elastic waist band and also the free ends of said elastic knee band 95 said leg member having oppositely extending closure portions foldable over upon opposite edges of said opening, and alternately securable upon opposite sides of said opening on the exterior of the garment.

2. As an article of manufacture, a pair of bloomers comprising a body portion terminating in an elastic waist band and having a pair of leg members terminating in elastic knee bands, said body portion and a leg member having a vertical opening at the outer side extending through the elastic 100 waist band and the elastic knee band, and fastening means for releasably connecting the free ends of the elastic waist band and also the free ends of said elastic knee band, 105 said leg member having a closure portion of less width than the length of the bloomers projecting from one edge of said opening, located wholly between the waist band and the knee band and foldable over upon the 110 opposite edge and releasably connected thereto.

3. A garment comprising front and rear members forming a pair of bloomers, said members comprising leg forming portions 115 terminating at the top in an elastic waist band and terminating at the bottom thereof in elastic bands for embracing the legs, said garment members having an opening extending up an entire side thereof, and means 120

- for closing said opening and comprising reversely extending flap portions wholly below the waist band and securable on opposite sides of said opening.
- 5 4. As an article of manufacture, a pair of bloomers comprising a divided waist portion provided with a waist band, means for securing together the juxtaposed ends of said waist band, leg portions, said waist portion and at least one of said leg portions having a vertical opening extending up an entire side thereof, means on opposite sides of said opening extending thereacross in opposite directions for closing the opening, and fastening devices for securing both of said means upon the exterior of the garment at opposite sides of the opening.
- 10 5. As an article of manufacture, a pair of bloomers comprising a divided waist portion provided with a waist band, means for securing together the juxtaposed ends of said waist band, leg portions, said waist portion and at least one of said leg portions having a vertical opening extending up an entire side thereof, and means for closing said opening and comprising a flap extension on one side of said opening wholly below the waist band adapted to extend across the opening, and means for securing
- 15 30 said flap extension at the other side of the opening.
6. As an article of manufacture, a pair of bloomers comprising a divided waist portion provided with a waist band, means for securing together the juxtaposed ends of said waist band, leg portions, said waist portion and at least one of said leg portions having a vertical opening extending up an entire side thereof, and means for closing said opening and comprising flap extensions on opposite sides of said opening adapted to extend thereacross in opposite directions, and means for securing said flap extensions at opposite sides of the opening.
- 35 7. As an article of manufacture, a pair of bloomers comprising a waist portion provided with an elastic waist band, leg portions terminating in elastic knee bands, said waist band and at least one of said knee bands being divided, means for securing together the juxtaposed ends of said waist band and the divided knee band, said waist portion and leg portion having a vertical opening up an entire side thereof, means on opposite sides of said opening extending thereacross in opposite directions for closing the opening and fastening devices for securing both of said means upon the exterior of the garment at opposite sides of the opening.
- 40 55 60

Signed at New York city, State of New York, this 29th day of March, 1923.

ALICE MORGANSTERN.
